TELEPHONE SYSTEM

Fritz Pfleiderer, Berlin-Wilmersdorf, Germany,
assignor to Siemens & Halske Aktiengesellschaft, Siemensstadt, near Berlin, Germany

Application May 25, 1932, Serial No. 613,349
In Germany June 4, 1931

8 Claims. (Cl. 179—27)

The present invention relates to a circuit arrangement for impulse transmission in communication systems, more particularly in telephone systems.

5 When setting up a toll connection with the assistance of an operator in telephone systems, it is necessary to transmit various switching operations over the junction lines connecting the operator's position with the required subscriber's exchange, such switching operations consisting of, for example, seizure, setting and release of connecting devices, setting up a speaking route for the operator in case the required subscriber's line is busy and cutting off an existing connection of low value. It will readily be appreciated that a faultless transmission of such a number of switching operations over junction lines, which frequently comprise two wires only, presents a difficult technical problem. In the case of known 10 arrangements these difficulties are overcome, if direct current is used as signalling current, by applying various potentials to one or both the speaking leads either in a uniform or varying sequence, which potentials then initiate the individual switching operations. In systems in which alternating current is used for the setting of the connecting devices over the junction lines the problem is solved by initiating the individual switching operations either by impulses 15 varying in length or impulses of equal length but differing as to number.

The present invention now provides a new and satisfactory solution of the problem over and above arrangements of known type by arranging 20 an impulse receiving relay at the incoming end of a junction line to influence switching devices which cause various switching operations to be carried out according to the number and length of the impulses received by said impulse receiving relay.

The accompanying drawings show an embodiment of the invention. An arrangement for a toll connection in telephone traffic is shown in which a voice frequency alternating current is 25 used for transmitting impulses over a long junction line.

The switching operation taking place when a toll connection is set up will be described below to the extent in which they are embodied in the 30 feature of the invention. Switching operations and circuits of no importance for the understanding of the invention have purposely been omitted.

It will be assumed that a call from a distant subscriber who requires a connection with the 35 subscriber T_n in exchange A is received at the

toll position FP. The operator at the toll position FP who now completes the connection between the distant subscriber and the required subscriber T_n first depresses the key BT and thereby produces a short impulse which passes 60 from the toll position FP over the junction line VL through the transformers which terminate said junction line, and through the impulse repeaters U_{e2} and U_{e3} to the final selector LW4 over which the required subscriber may be accessible.

The depression of the key BT causes relay C1 at the toll position FP to be energized. Relay C1 closes the following circuit for relay J1: earth, contacts 1c1, 22u1, winding of relay J1, battery, 70 earth. Relay J1 is energized and applies the alternating current source of supply WQ to the two speaking leads over its contact 4j1 and 5j1. This sets up a short impulse to the signal receiver SE, tuned to a voice frequency, in the repeater 75 U_{e2} in exchange A over the junction line VL, terminating in the two transformers. The duration of this impulse depends upon the energization of relay U1. The following circuit is closed for this relay U1 when relay C1 is energized: 80 earth, contacts 1c1, 2c1, winding of relay U1, battery, earth. Relay U1 is energized with slow action. The circuit for relay J1 is opened after relay U1 was energized and consequently opened its contact 22u1.

The short impulse imparted to the signal receiver SE causes relay A2 in the repeater U_{e2} to be energized. Relay A2, over its contact 1a2, closes a circuit for relay J2. In addition, relay T2 is energized over earth, contact 7a2, 5v2, 90 winding of relay T2, resistance Wj7, battery, earth. Relay T2 is placed in a locking circuit over its own contact 4t2. The following circuit for relay C2 is closed due to the energization of relay J2: earth, contact 13j2, winding of relay 95 C2, contact 11p2, battery, earth. The slow acting relay V2 also is energized over contact 18j2 by relay J2. The energization of relays C2 and V2 prevents relay G2 from being energized since these relays form a short circuit for relay G2 by 100 the closing of their contacts 8c2 and 10v2. Relay C3 in the repeater U_{e3} is energized over contact 38c2 due to the energization of relay C2. Relay C3 in turn closes the circuit to the final selector LW4 by means of contact 12c3 in which 105 relay C4 is energized. Relay C4 prepares the circuit to the subscriber T_n which extends over the test relay P4 and the c-wiper of the final selector LW4 by closing its contact 1c4.

Relays A2, J2 and V2 in the repeater U_{e2} re- 110

lease at the end of this impulse. Relay G2 is now energized in the following circuit due to the release of relay V2: earth, contact 8c2, winding of relay G2, battery, earth. Relay T2 remains energized over its contact 4t2 as mentioned above. Contacts 29g2 and 30g2 are closed when relay G2 is energized and the closing of these contacts prepares the circuit for the transmission of the selecting impulses.

10 It should be mentioned in this connection that when the impulse reaches the repeater Ue2 and relays J2 and T2 are energized over contacts 22j2 and 21t2 a circuit is closed for the rotary magnet Dm of a discriminator so that said discriminator moves one step. This has no consequence in the present case due to the fact that relay T2 remains energized. After the release of relays J2 and V2, however, a circuit is closed over earth, interrupter RU, wiper dm1 of the discriminator contacts 19v2, 20j2, rotary magnet Dm, battery, earth, in which the discriminator is restored to normal.

The operator at the toll position FP now commences to dial for the purpose of setting the final selector LW4 to the required subscriber's line. 25 The impulse contacts nsj are closed at each impulse which causes relay J1 to be intermittently energized and de-energized in the following circuit: earth, impulse contact nsj, contacts 3c1, winding of relay J1, battery, earth. The impulses 30 are transmitted over the junction line VL to the signal receiver SE and thence to relay A2 by means of contact 4j1 and 5j1 which re-connect the alternating current source of supply WQ to the speaking leads. Relay A2 is energized and 35 re-energizes relays J2 and V2. The impulses are transmitted from the repeater Ue2 to the repeater Ue3 by applying earth to the a-lead and control potential to the b-lead. The appropriate circuits being of no importance for the invention have 40 not been shown. In a similar manner the impulses are transmitted from the repeater Ue3 to the final selector LW4 by applying earth to the a-lead and control potential to the b-lead. Even these circuits have no bearing on the nature of 45 the invention and therefore have been omitted. When the final selector LW4 has been duly set to the subscriber Tn by the impulse series which the toll operator transmitted, the test relay P4 is energized if the line is idle. The test relay 50 guards the line in known manner by means of its contact 15p4 and switches through the two speaking leads with the aid of its contacts 5p4 and 6p4. It also applies a potential to the b-lead over contact 9p4 and consequently closes the following 55 circuit for relay W3 in the repeater Ue3: earth, battery, resistance Wj8, contact 9p4, b-lead, contacts 7r3, 8v3, winding I of relay W3, earth. Relay W3 is energized and placed in the following locking circuit: earth, contacts 13c3, 14w3, winding II of relay W3, battery, earth.

The operator at the toll position FP who receives no busy signal if the subscriber's line is idle now depresses the ringing key RT an extended period. This connects the ringing current source of supply in the repeater Ue3 to the line leading to the required subscriber Tn. The pressing down of the ringing key RT namely, causes relay J1 to be re-energized over earth, key RT, contact 3c1, winding of relay J1, battery, earth. Relay J1, in the manner described above, sends a long impulse by means of its contacts 4j1 and 5j1 to the voice frequency receiver SE in the repeater Ue2. Relay A2 which is then energized in turn re-energizes relay J2 and relay 75 J2 causes the slow acting relay V2 to be energized.

gized. Relay V2 closes its contact 6v2 and due to the longer impulse which causes relay T2 to be short circuited an extended period over earth, contacts 7a2, 6v2, it releases with slow action. The following circuit for the rotary magnet Dm of the discriminator was closed on the energization of relay J2: earth, contacts 22j2, 21t2, winding of the rotary magnet Dm, battery, earth. The rotary magnet Dm advances the switch wipers of the discriminator one step. The switch wiper dm2 then reaches position 1 over which the following circuit for relay X2 is closed after relay T2 has released: earth, contacts 14v2, 15t2, switch wiper dm2, winding of relay X2, battery, earth. Relay X2 is energized and closes a circuit for relay B3 in the repeater Ue3 as follows: earth, battery, contacts 23x2, 31t2, 34j2, 30g2, 35v2, winding of relay B3, battery, earth. Relay B3 forms the following circuit for relay R3, earth, contacts 19b3, 18v3, winding of relay R3, battery, earth. Relay R3 is energized and, by closing its contacts 10r3 and 11r3, connects the ringing current source of supply RQ to the two speaking leads passing over the final selector LW4 to the subscriber Tn. The subscriber Tn is 100 now called by the ringing signal. The further circuits formed when the subscriber lifts his receiver have not been shown since they are of no interest in the present case. At the end of the impulse series the discriminator is restored to 105 normal after the release of relays A2, J2 and V2 over: earth, interrupter RU, switch wiper dm1, contacts 19v2, 20j2, winding of the rotary magnet Dm.

The case will now be considered when the 110 called subscriber Tn is engaged in a local call at the time when the final selector LW4 is set to his line. In such a case the operator at the toll position FP must have the facility of being able to communicate with the subscriber Tn in order 115 to inform him of the incoming toll call and request him to replace his receiver. With the object of cutting in on the existing local call the operator depresses the switch key AT1 and AT2 at the toll position FP. This causes first a short 120 and then a long impulse to be transmitted in the following manner: Relay J1 is energized in the following circuit when the key AT1 is depressed: earth, key AT1, contacts 9e1, and 8r1 in parallel, contact 3c1, winding of relay J1, battery, earth. Relay J1 transmits an impulse to the repeater Ue2. Pressing down key AT2 causes 125 relay E1 to be energized over: earth, key AT2, winding of relay E1, resistance Wj3, battery, battery, earth. Relay E1 opens its contact 7e1, 130 whereupon relay R1 is energized in the following circuit: earth, key AT2, winding of relay R1, resistance Wj2, battery, earth. Relay R1 is energized and short circuits relay E1 by means of its contact 10r1 so that relay E1 releases with slow 135 action. Relay R1, in addition, opens its contact 8r1 which cuts off the circuit for relay J1 during the release period of relay E1. This circuit is re-closed after the release of relay E1 until the switch keys AT1 and AT2 are released. Relay J1 is energized a corresponding period. In order to prevent relay E1 from being re-energized in the period during which the key AT is depressed and consequently cause a second short impulse to be transmitted, the short circuit for relay R1 is 140 opened at contact 6r1.

In the repeater Ue3 the short and the succeeding long impulse received from the signal receiver SE and relay A2 causes the discriminator Dm to be advanced two steps over the same circuit as 150

that described in connection with the calling operation. The long impulse causes relay T2 to release which in turn causes relay Y2 to be energized over earth, contacts 14v2, 15t2, wiper dm2 of the discriminator in position 2, winding I of relay Y2, battery, earth. Relay Y2 closes its contacts 2y2 and 3y2 and consequently applies earth to the a- and b-leads over the two similar chokes DR1 and DR2. Applying earth to the a-lead 10 causes the connecting up, and applying earth to the b-lead is carried out with the object of obtaining a symmetrical load necessary to gain a satisfactory speech transmission from the toll position FP to the subscriber Tn. Relay Y2 is placed 15 in the following locking circuit until the succeeding signal is sent out: earth, contact 16t2, 17y2, winding II of relay Y2, battery, earth. Relays A2, J2, V2 are released at the end of the long impulse. The discriminator advances into its original position. Applying earth to the a-lead now 20 causes the following circuit for relay A3 in the repeater Ue3 to be formed: earth, choke Dr1, contacts 2y2, 28v2, winding of relay A3, battery, earth. Relay A3 closes the following circuit for relay V3: 25 earth, contacts 17a3, 15w3, winding of relay V3, battery, earth. Relay V3 is energized and closes a circuit over earth, battery, contacts 9v3, 7r3, 7a4, winding of relay Y4 in which circuit relay Y4 in the final selector LW4 is energized. Relay Y4 30 is energized and by closing its contacts 3y4 and 4y4 causes the still opened speaking leads to be bridged at contacts 6p4 and 5p4. This enables the operator at the toll position FP to communicate with the subscriber Tn by means of her speaking set connected up over the keys ST1 and ST2 so that she can inform him of the incoming toll call. If the subscriber who is in communication with the subscriber Tn does not replace his receiver, the operator at the toll position FP is 35 in a position to cut off the connection.

With this object in view she throws over the cut off keys TT1 and TT2 which causes two short and one long impulse to be transmitted. Relay J1 is energized over key TT1 in the following circuit: earth, key TT1, contacts 19k1, 15/1, 3c1, winding of relay J1, battery, earth. Relay J1 is energized and transmits a short impulse over the junction line VL to the voice frequency receiver SE in the repeater Ue2. Depressing the cut off 40 key causes relay F1 to be energized over earth, key TT2, winding of relay F1, contact 17g1, battery, earth. By means of contact 15/1 relay F1 cuts off the above described circuit for relay J1. The following circuit for relay G1 is then formed: 45 earth, contacts 11k1, 12f1, winding of relay G1, battery, earth. Relay G1 is energized and closes a fresh circuit for relay J1 as follows: earth, key TT1, contacts 13g1, 3c1, winding of relay J1, battery, earth. Relay J1 is energized and transmits 50 a second short impulse to the signal receiver SE in the repeater Ue2. The following circuit for relay K1 is closed in consequence of the energization of relay G1: earth, key TT1, contact 16g1, winding of relay K1, battery, earth. Relay K1 is placed in a locking circuit over its contact 14k1. The energization of relay G1 also cuts off the circuit for slow releasing relay F1 by means of contact 17g1. The opening of contact 19k1 prevents relay K1 from transmitting an impulse in error 55 to the repeater Ue2. Relay G1 is released when contact 11k1 is opened. The release of relay G1 causes relay F1 to be re-energized. Relay F1 now opens its contact 15/1 permanently. The long impulse is transmitted due to relay D1 being energized on the energization of relay K1 over: earth, 60 key TT1, contact 20k1, winding of relay D1, battery, earth. A circuit for relay J1 is closed over earth, key TT1, contacts 18d1, 3c1, winding of relay J1, battery, earth when relay D1 is energized. Relay J1 is energized in this circuit until the cut off key TT1 is opened and consequently the two relays K1 and D1 are released. 65

In the repeater Ue2, the relays J2, T2 and V2 are re-energized over relay A2. Contact 16t2 first breaks the existing locking circuit for winding II of relay Y2. Relay T2 remains energized during the short impulses. The two short and the succeeding long impulses cause the rotary magnet Dm of the discriminator to be energized and de-energized three times. Accordingly, it advances 70 the switch wipers three steps. The switch wiper dm2 then reaches position 3. The long impulse causes relay T2 to be short circuited over earth, contacts 7a2, 6v2. Relay T2 then releases, whereupon relay Z2 can be energized over: earth, contacts 14v2, 15t2, wiper dm2, contact 3 of the discriminator, winding of relay Z2, battery, earth. Relay Z2 is energized and for the duration of the long impulse applies earth to the a-lead over contacts 25s2, 26t2, 27j2, 29g2, 36v2, and a potential 75 to the b-lead over contacts 24s2, 21t2, 34j2, 30g2, 35v2. 80

This causes relays A3 and B3 in the repeater Ue3 to be energized. Relay A3 is energized in the following circuit: earth, contacts 25s2, 26t2, 27j2, 29g2, 36v2, winding of relay A3, battery, earth. Relay A3 closes its contact 17a3 which causes relay V3 to be energized over earth, contacts 17a3, 15w3, winding of relay V3, battery, earth. Relay B3 was energized over: earth, battery, contact 85 24s2, 31t2, 34j2, 30g2, 35v2, winding of relay B3, earth. 90

The relays A4 and Y4 in the final selector LW4 are now energized, relay A4 in the following circuit: earth, contacts 5v3, 4b3, 6r3, winding of relay A4, battery, earth, and relay Y4 is energized over: earth, battery, contacts 9v3, 7r3, resistance W78, winding of relay Y4, earth. Earth is now applied to the b-lead over contacts 1c4, 2c4, 14s4, 4y4. If the required subscriber Tn was the calling party in the local call, the preselector of the subscriber Tn will be released over the seized first group selector by earth being applied to the b-lead with the result that the conversation is now 95 cut off and the final selector LW4 is able to operate. If the subscriber Tn was the called party in the local call, the test relay of the final selector, seized for the local call, is short circuited by cut off earth being applied direct to the c-lead over contacts 1c4, 2c4, 13y4, 12a4, which releases 100 105 the c-lead so that the test relay P4 is able to operate as soon as the cut off key is restored to normal. 110

The release of the relays in the repeater Ue2 is initiated in the manner repeatedly described 115 above, after the end of the last impulse, by the release of relay A2 which in turn cuts off the circuit for relay J2 and subsequently for relay V2 also. When relays J2 and V2 have been released, a circuit over which the discriminator is advanced into its original position is formed afresh for the rotary magnet Dm of the discriminator as follows: earth, interrupter RU, switch wiper dm1, contacts 19v2, 20j2, winding of the rotary magnet Dm, battery, earth. The release of relay 120 C2 and consequently also relay G2 at the end of the conversation is caused by contact 11p2 of a not shown relay P2. This relay is energized over the toll position FP while the release is being carried out. The switching operations in connection 125 130 135 140 145 150 155

therewith are of no importance for the invention and therefore have been omitted. The release of relay C2 causes the release of all the succeeding connecting devices.

5. What is claimed is:

1. In a communicating system, means for transmitting a variable number of short impulses and a succeeding long impulse, and receiving means responsive to said long impulse to perform a switching operation dependent upon the number of preceding short impulses.

10 2. In a communicating system, a transmitter, a receiver, means at the transmitter for transmitting a series of impulses composed of a variable number of short impulses succeeded by a long impulse, a plurality of responsive devices at said receiver, means responsive to the transmitted short impulses for predetermining the one of said responsive devices that corresponds to the number of short impulses received, and means responsive to the succeeding long impulse for actuating the predetermined responsive device.

15 3. In a telephone system wherein a connection incoming over a trunk line may be further extended by way of a pair of talking conductors, receiving means arranged to respond selectively to a series of impulses received over said incoming trunk line and comprising a variable number of short impulses followed by a long impulse, and means controlled by said receiving means for applying a combination of potentials to the two talking conductors of the extended connection, the combination of potentials differing according to the number of short impulses in the received series.

20 4. In a switching system, a switch having a contact bank and a co-operating wiper, means for transmitting a series of impulses to said switch composed of a variable number of short impulses and a succeeding long impulse, means responsive to said short impulses for positioning the wiper of said switch onto a contact which depends upon the number of short impulses received, and means responsive to the long impulse for closing a circuit including the wiper of said switch and the contact on which it is positioned.

25 5. In a switching system, a receiver responsive to short and long impulses, a self-locking relay, means controlled by a long impulse for operating said self-locking relay to close its locking circuit dependent upon the long impulse being preceded by a predetermined number of short impulses, and means responsive to a further received impulse for opening said locking circuit to enable said relay to restore.

30 6. In a long-distance telephone system, a toll line, automatic switching apparatus at the distant end of said toll line, means for transmitting impulses of voice-frequency alternating current over said toll line, translating means at the distant end of said toll line for translating said voice-frequency impulses into suitable impulses for positioning said automatic switching apparatus to extend said toll line, and means at the distant end of said toll line responsive to the transmission of further impulses of voice-frequency current for performing incidental controlling operations.

35 7. In a telephone system, a toll line extending to an automatic exchange, means including a toll connector for extending said toll line to subscribers' lines in said exchange, means for transmitting impulses of alternating current over said toll line to control the setting of said switch, a discriminating switch, means for controlling said switch by additional impulses of alternating current transmitted over said toll line, and circuits controlled by said switch for controlling the operation of said connector in ringing the called party if idle, offering the call if the called party is busy, and forcing the release of the connection involving the called line.

40 8. In a telephone system, a toll connector, a line over which setting impulses are transmitted to position said connector on a called line, a discriminating switch associated with said connector, means for variably operating and reoperating said switch a number of times while the connector stands on the called line, and circuits controlled by said switch for initiating various operations in the connector.
